CLAIM

The ornamental design for a hat with football-shaped bill as shown and described.

DESCRIPTION

FIG. 1 is a top front right perspective view of a hat with football-shaped bill;

FIG. 2 is a front elevational view of the hat with football-shaped bill;

FIG. 3 is a left side elevational view of the hat with football-shaped bill, the right side is a mirror-image thereof;

FIG. 4 is a rear elevational view of the hat with football-shaped bill;

FIG. 5 is a top plan view of the hat with football-shaped bill; and,

FIG. 6 is a bottom plan view of the hat with football-shaped bill.

The broken lines along the exterior surface of the hat with football-shaped bill in FIGS. 1-5 depict claimed stitching. The broken line in FIG. 6 defines the bounds of the hat with football-shaped bill and forms no part of the claimed design.
